(57) CLAIM

The ornamental design for a portable oil drum, as shown.

DESCRIPTION

FIG. 1 is a front view of a portable oil drum showing my new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

Those portions of the illustrated design illustrated by broken lines form no part of the claimed design.
